UNITED STATES PATENT OFFICE.

GEORGE C. BLICKENSDERFER, OF STAMFORD, CONNECTICUT, ASSIGNOR
TO THE BLICKENSDERFER MANUFACTURING COMPANY, OF NEW
YORK, N. Y.

TYPE-WRITING MACHINE.

SPECIFICATION forming part of Letters Patent No. 432,298, dated July 15, 1890.

Application filed July 5, 1889. Serial No. 316,590. (No model.)

To all whom it may concern:

Be it known that I, GEORGE C. BLICKENSDERFER, a citizen of the United States, residing at Stamford, in the county of Fairfield and State of Connecticut, have invented certain new and useful Improvements in Under-scoring, Canceling, and Space-Filling Attachments for Type-Writing Machines, of which the following is a specification.

10 This invention relates to means for under-scoring words and lines made by type-writing machines, canceling words or lines printed by said machines, and for filling in the spaces left between said words or lines.

15 My invention has for its object to provide a simple, economically-constructed, durable, and quickly-operated form of under-scoring, canceling, and filling-in-blank-space device, which is independent of the key-levers or 20 other operative parts of the type-writer.

25 My invention accordingly consists of the under-scoring, canceling, and filling-in-blank-space device, as will be hereinafter described in the specification, and pointed out in the claims.

30 Referring to the accompanying drawings, which are hereby made a part of the specification, Figure 1 represents a top plan of part of a form of type-wheel type-writing machine, which is the subject-matter of another application filed by me of even date herewith, Serial No. 316,951, having my improved under-scoring, canceling, and blank-filling-in space devices attached thereto in the position that they take when not in use. Fig. 2 35 represents a longitudinal section of the under-scoring device, and Fig. 3 a side elevation showing one of the devices in position to act upon the matter on the paper or platen, and 40 the other part in position when not in use.

45 A represents the top of the machine; B, the platen or roller of the paper-carriage; D, the under-scoring device and D' the canceling device, both of which are suitably pivoted or otherwise supported on the frame or other fixed part of the machine, so as to be movable to and from the roller B. As shown in the drawings, these said devices are pivoted at their ends d to standards a on the machine.

Each device consists of a casing d', having 50 an open face or top c, preferably, and provided with a shaft d², carrying an inking-pad d³, above which and suitably journaled is another shaft e, carrying a marking wheel or roller f, part of the periphery of which projects through and beyond the open face or top c, as indicated more plainly in Figs. 2 and 3, for under-scoring, canceling, and filling in blank spaces. The casing d' is in the form of a receptacle, preferably of an oblong configuration, as indicated, and is open at its top or upper end for the canceling or under-scoring device to project through. The shaft of the canceling and under-scoring device is parallel with the bottom of the casing and at 55 right angles to its pivot or hinge connection. Between the shaft of the under-scoring and canceling device and the bottom of the casing a rotating inking-pad is placed. By so locating the pad the ink will not seep to one 60 end thereof, as would be the case if the normal position of the pad were vertical instead of horizontal. The pad therefore, when raised for operation, will always present an inked surface to the canceling or under-scoring device 65 for any extended length of operation of the same.

70 It is obvious that one device D, with a roller or wheel f, can be used for under-scoring, canceling, or filling in blank spaces; but I prefer to use a distinct device for each purpose, as the canceling and blank-space filling can be made without changing the position of the roller B, whereas in under-scoring the roller B 75 must be given a short turn to raise the printed matter above the wheel or roller f. By providing two separate devices D and D', I am 80 enabled to underscore without changing the position of the roller B, and this saves time. The under-scoring and canceling wheel or roller 85 f may be similar in form, and if the periphery be provided with teeth that make marks like periods or hyphens no other means need be used for revolving the feeding-pad for inking wheel f, as its teeth will catch in the pad 90 and turn it so that fresh inking-surfaces will be continuously presented to the wheels f. 95

In practice I prefer to use a wheel f having

two parallel rows of teeth or of periods or hyphens; but this is immaterial. Where a distinct device D' is used for canceling and filling in blank spaces, I prefer to make the 5 wheel f of the underscoring device D with a V-shaped periphery, so as to make a continuous fine line under the matter underscored. In such case I also arrange the underscoring-wheel f on its shaft in such manner as to bring 10 it under the matter to be underscored, and thus dispense with the shifting of the roller B. When this is done, a second toothed wheel f² is placed upon the shaft e, for turning the inking-pad d³, as the V-shaped wheel will not 15 turn said pad, the wheel f being arranged, or is of such a diameter, as not to project beyond the face or top c of the casing d'. The ink is applied to the pads through one of the 20 sides of the casing, which is left open or cut away for that purpose, as more plainly indicated in Fig. 3 by the dotted lines c' c'. This open side may be closed by any suitable partition G, pivoted at any suitable point. If 25 both the underscoring and canceling devices be used, I prefer to hinge the partition G in the pivot at a point between the two casings and have the open sides c' in said casings opposite each other, so that one partition will close both openings when the two devices are 30 in their normal position, as more plainly indicated in Fig. 1. When one of the devices D D' is raised, the partition covers only one of the openings c'; but as they are not separated for any length of time evaporation of 35 the ink and accumulation of dust in the casings will be very small. When both devices are used, each may have different-colored inks in the pads, so that there will be a clear distinction between the two.

40 The operation is as follows: If it be desired to underscore, or cancel, or fill in blank spaces, and only one device be used for all the above-noted purposes, the device is turned up against the paper on the platen or roller B. If for canceling or filling in blank spaces, the paper-carriage-supporting roller B is moved by hand in a longitudinal direction to produce the result. If for underscoring, the roller B is turned the required distance, and 45 the carriage is then moved in the longitudinal direction, the same as in canceling. When both devices D and D' are used, the turning of the roller B is not necessary in underscoring, as the wheel is so arranged upon its shaft as to bring the wheel at the desired point to do the underscoring. In any case it will be noted that the devices D D' are not subject to or 50 under the control of the actuating mechanism for the type-writing machine.

55 It is obvious that with a few minor changes this device D can be applied to all kinds of type-writing machines; and the construction and operation of the device may be

greatly varied without departing from the spirit of my invention, and hence I do not 65 limit myself to any particular construction of the device, nor to the manner of pivoting or hinging the same to the machine, nor to the location of the device with reference to the roller or platen B.

I do not herein broadly claim the combination, with a sliding paper-carriage, of the underscoring device affixed to the frame of the machine, so as to be independent of the key-levers and other operative or movable parts 75 of the machine, as the same is claimed in application Serial No. 316,591 aforesaid.

I herein claim only the specific form of the canceling, underscoring, and blank-space-filling device and the separate canceling and 80 underscoring devices in themselves, as hereinafter set forth in the claims, without reference to the sliding or movable paper-carriage; but in another pending application of even date herewith, Serial No. 316,591, I broadly 85 claim the combination, with a sliding or movable paper-carriage, of an underscoring or canceling device mounted upon a fixed or immovable part of a type-writing machine, so as to be moved to or away from the paper- 90 carriage.

What I claim is—

1. A type-writer underscoring or canceling device comprising a pivoted casing in the form of a receptacle having an open face or 95 top, a marking-wheel projecting through said open face and having a shaft parallel with the bottom of the casing, and an inking-pad between said marking-wheel and the casing-bottom, substantially as set forth. 100

2. The underscoring device D, comprising a freely pivoted or hinged casing having an open side or face, and a marking-wheel and inking-pad journaled on said casing, with their shafts parallel to each other and the bottom 105 of the casing and at right angles to the pivot-shaft for said casing, substantially as set forth.

3. In a type-writing machine, a separate underscoring device, a separate canceling device, both of which have inking-pads and marking wheels or rollers and adjacent open sides, a slide between said sides and said devices, and the slide hung upon a common support or pivot, substantially as set forth. 110

4. In a type-writing machine, a separate underscoring device, a separate canceling device, and both of said devices provided with an inking-pad and a marking wheel or roller, substantially as set forth. 115

In testimony whereof I affix my signature in presence of two witnesses.

GEORGE C. BLICKENSDERFER.
